Primary Examiner — Samantha Wood

(57) **CLAIM**

The ornamental design for a faucet, as shown and described.

DESCRIPTION

FIG. 1 is a perspective view of a faucet showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the faucet taken from the circle part in FIG. 2; and,

FIG. 9 is an enlarged view of the faucet taken from the circle part in FIG. 7.

The broken lines depict portions of the faucet that form no part of the claimed design.

1 Claim, 9 Drawing Sheets
